UNITED STATES PATENT OFFICE.

WILLIAM K. ANDERSEN, OF BROOKLYN, NEW YORK.

DESIGN FOR A MOTOR-VEHICLE-RADIATOR CAP.

Application filed November 3, 1925. Serial No. 15,329. Term of patent 7 years.

To all whom it may concern:

Be it known that I, WILLIAM K. ANDERSEN, a subject of the King of Denmark, residing at Brooklyn, in the county of Kings and State of New York, have invented a new, original, and ornamental Design for a Motor-Vehicle-Radiator Cap, of which the following is a specification, reference being had to the accompanying drawing, forming part thereof.

Figure 1 is a perspective view of a motor vehicle radiator cap showing my new design, and

Fig. 2 is a side elevation thereof.

I claim:

The ornamental design for a motor vehicle radiator cap, as shown.

WILLIAM K. ANDERSEN.
